UNITED STATES PATENT OFFICE.

JACOB LOOPO, OF BROOKLYN, NEW YORK.

DESIGN FOR VENICE LACE.

60,691.

Specification for Design. Patented Mar. 21, 1922.

Application filed November 23, 1921. Serial No. 517,367. Term of patent 3½ years.

To all whom it may concern:

Be it known that I, Jacob Loopo, a citizen of the United States, residing in the city of New York, borough of Brooklyn, in the county of Kings and State of New York, have invented a new, original, and ornamental Design for Venice Lace, of which the following is a specification, reference being had to the accompanying drawing, forming a part thereof.

The figure is a plan view of my new design for Venice lace.

I claim:

The ornamental design for Venice lace as shown.

JACOB LOOPO.
